UNITED STATES PATENT OFFICE

FRED S. CARR, OF NEWTON, MASSACHUSETTS; MOSES F. CARR, EXECUTOR OF SAID FRED S. CARR, DECEASED, ASSIGNOR, BY MESNE ASSIGNMENTS, TO UNITED-CARR FASTENER CORPORATION, OF CAMBRIDGE, MASSACHUSETTS, A CORPORATION OF MASSACHUSETTS

TRIMMING INSTALLATION

Application filed February 26, 1925. Serial No. 11,698.

This invention aims to provide an improved trimming installation and improved separable fastening means, particularly though not exclusively for use therewith.

5 Reference is made to a division of this application, Serial No. 52,320, filed August 25, 1925.

In the drawings, which illustrate two preferred embodiments of my invention:—

10 Figure 1 is an elevation view of a window and window frame of a vehicle body or the like, showing one use of my invention;

Fig. 2 is a section on the line 2—2 of Fig. 1, showing the trim strip secured to the window frame by stud and socket fastening means;

15 Fig. 3 is a plan view of a portion of the trim strip showing a stud unit secured thereto;

Fig. 4 is a plan view of a stud unit for use 20 with a trim strip;

Fig. 5 is a side elevation of the stud unit illustrated in Fig. 4; and

25 Fig. 6 is a section similar to Fig. 2, the stud unit being reversed and showing a depressed portion in the frame part for receiving the casing part of the stud unit.

Referring to the embodiment of my invention illustrated in Figs. 1 through 5 of the drawings, I have shown a trimming installation particularly, though not exclusively, useful in automobile body construction. The installation illustrated includes the body or frame part 1 which, in some instances, may be covered with upholstery 2 (Fig. 2), the 30 trim strips 3 and a plurality of reversible double headed stud units 4 for securing the trim strips to the frame part 1.

Trim strips or finishing strips for automobile body work have heretofore usually been 40 constructed of wood and secured to the frame part by screws, nails or the like. While wooden trim strips may be used in connection with my invention, I prefer to provide metal trim strips 3 (Fig. 2), which are hollow and are 45 pressed from single pieces of metal. These

strips are strong, durable, neat in appearance and can be made quickly and very inexpensively.

The stud units are of a novel construction and include two substantially similar socket-engaging stud parts, each of which is provided with a contractile and expansible head 5 and a neck 6. The base portion of one of the studs provides a casing 7 which contains the base 8 of the other stud member. The inside diameter of the casing 7 is larger than the diameter of the base 8 so that each stud member shifts relative to the other, for purposes more fully hereinafter described.

50 The body part 1 is prepared to receive the trim strip by providing therein a plurality of stud-receiving apertures 9. Likewise the trim strips 3 are provided with depressed portions or pockets 10 and stud-receiving apertures 11 which may be formed at the inner 55 face of the strip at the same time that the strip is formed.

50 The body part 1 is prepared to receive the trim strip by providing therein a plurality of stud-receiving apertures 9. Likewise the trim strips 3 are provided with depressed portions or pockets 10 and stud-receiving apertures 11 which may be formed at the inner 55 face of the strip at the same time that the strip is formed.

60 In assembling the installation, the upholstery, if used, is first stretched over the frame part, and holes 12 formed therein to expose 70 the stud-receiving apertures 9 presented by the frame. The stud units may then be secured to the frame part 1 by forcing one of the heads 5 of each stud-unit into an aperture 9. Each casing 7 overlies and seats 75 against the upholstery to hold it in place. If desirable, the stud-units may be secured to the trim strips 3 in the first instance instead of the frame. The trim strips 3 are thereafter secured to the body part 1 by pressing 80 the remaining unengaged heads of the stud-units into the remaining stud-receiving apertures so that the strip will be pulled tightly 85 against and conceal the edge of the upholstery. During engagement of the stud heads in the apertures, each stud part may shift laterally relative to its cooperating stud part if necessary for alignment with its cooperating aperture in either the frame part 1 or the strip 3. The pockets 10 receive the casing 90

portions 7 of the stud units (Figs. 2 and 3) so that the inner face of the trim strip 3 may lie close to frame part, there being no space between except that taken up by the upholstery 2 if there be any. Thus I have provided a trim strip installation which may be easily and quickly assembled and disassembled.

Referring now to Fig. 6, I have shown my invention as it appears when the stud unit is reversed. In this instance, the stud head that engaged the trim strip 3, as shown in Fig. 2, is shown engaging the body part 1 and the pocket 10 is formed in the frame part 1 instead of in the trim strip 3.

Assembly of the parts of the installation is substantially the same as described in connection with Figs. 1 through 5.

While I have shown and described preferred embodiments of my invention, it will be understood that changes involving omission, substitution, alteration and even reversal of parts may be made without departing from the scope of my invention, which is best defined in the appended claims.

25 **Claims:**

1. A trimming installation comprising, in combination, a trim strip having a stud-receiving aperture at the inner face thereof, a frame part having a stud-receiving aperture, 30 a depressed portion provided in one of said parts to form a pocket between said apertures and a double snap fastener stud unit having a central flange portion, said stud unit presenting two stud heads extending in opposite directions and engaged in said apertures to secure said trim strip to said frame part and said central flange portion located in the pocket provided between said parts.

2. A trimming installation comprising, in combination, a trim strip part having stud-receiving means at the inner face thereof, a frame part having stud-receiving means, a depressed portion formed in one of said parts and providing a pocket between said 45 stud-receiving means and a double stud unit having a central flange portion located in said pocket and a stud head at each side of said central flange portion engaged in said stud-receiving means to secure said 50 trim strip part to said frame part and said central flange portion embodying means for holding the studs in assembled relation and permitting lateral shifting of said stud heads relative to each other for alignment with 55 said stud-receiving means.

3. A trimming installation comprising, in combination, a pressed metal frame part having a stud-receiving aperture of fixed dimensions, an upholstery fabric overlying said 60 frame part and cut away to expose the aperture in said frame part, a pressed metal trim strip applied to said frame part, an aperture of fixed dimensions located at the inner face of said strip, a pocket provided by one of said 65 parts and surrounding the aperture in said

part and two stud members secured together loosely to permit lateral shifting of one stud relative to the other and having a casing portion between them, each of said stud members having a resilient head passing through 70 said apertures thereby securing the trim strip to said frame with the fabric gripped between, and said casing portion being located in said pocket.

In testimony whereof, I have signed my 75 name to this specification.
